TWO-STAGE ISOMERIZATION OF NORMAL PARAFFINS

Emmett H. Burk, Jr., Hazelcrest, John Mooi, Homewood, and Owen H. Thomas, Chicago, Ill., assignors to Sinclair Refining Company, New York, N.Y., a corporation of Maine

No Drawing. Filed May 7, 1959, Ser. No. 811,537

10 Claims. (Cl. 260—683.66)

This invention relates to a hydrocarbon conversion process and particularly pertains to a two-stage process for isomerizing straight chain aliphatics to produce branch chain aliphatic structures, e.g. isomeric structures of n-paraffins, which are especially useful in providing gasoline components of high octane rating.

In recent years automobile manufacturers have steadily increased the compression ratios of their spark-ignition engines as a means of obtaining more power and greater efficiency. As the compression ratios of the engines increases, the hydrocarbon fuel employed must be of higher octane rating to provide efficient knock-free operation notwithstanding that fuel octane rating can be increased through the addition of tetraethyl lead, and other undesirable aspects of engine operation, for instance pre-ignition, can be overcome by the use of other additive components. Thus the problem remains for petroleum refiners to produce higher octane base hydrocarbon fuels under economically feasible conditions.

These refiners now have installed a substantial number of units for reforming straight run petroleum fractions in the presence of free hydrogen and over a platinum metal-alumina catalyst to obtain relatively high octane products. Primarily these products, frequently called reformates, are blended with other gasoline components such as thermal and catalytically cracked gasolines, alkylate, etc., and additives such as tetraethyl lead in obtaining present-day motor fuels. The reforming operation has a number of disadvantages. First, as the octane requirements of the blended engine fuels rise, the octane quality of the reformate must also increase if the blends be otherwise unaltered. This increase results in a substantial reduction in yield particularly in obtaining reformates having octanes (RON neat) of the order of 90 to 95 or above. When the severity of the operation is increased, the platinum metal-containing catalyst becomes fouled more often with carbonaceous deposits which requires more frequent regenerations or replacements. The platinum metal-alumina catalysts are relatively expensive, and either replacement or withdrawal from use during regeneration materially increases the cost of providing a given volume of reformate. These and other factors affecting the yield-octane number-cost relationship make it desirable for the refiner to consider various ways in which high octane hydrocarbon fuel components can be obtained by employing processing methods other than the platinum metal-alumina catalyst reforming operation.

One method now under consideration by petroleum refiners for obtaining stocks of higher octane value involves the isomerization of C_4 to C_9 n-paraffinic hydro-

2

carbons, that is n-butane, n-pentane, n-hexane, n-heptane, n-octane, n-nonane and their mixtures with each other and with other hydrocarbons in the same approximate boiling range. In general, as the side chain branching of these n-paraffins increases, their octane ratings rise. A number of catalysts are known as being useful in this type of operation. An example of such a system is that described in U.S. Patent No. 2,798,105 wherein a platinum-alumina catalyst is employed to isomerize n-butane and n-pentane at temperatures upwards of 600° F. At such temperatures the thermodynamic equilibrium between the feedstock and the isomeric product is such that conversion is unduly limited which means that the product contains undesirably large amounts of n-paraffins. Due to the low octane rating of the n-paraffins a given refiner may not be able to blend the entire product from the high temperature isomerization system directly into his gasolines. Rather, under present commercial conditions he will most likely be required to separate the n- and iso-paraffins in the product stream by distillation and then recycle all or a part of the unconverted n-paraffins to the isomerization reaction system. It is, of course, immediately seen that the decreased yield of isomer structures at the high reaction temperatures is disadvantageous, and in addition the provision of the required distillation facilities materially adds to the cost of octane enhancement.

In a process described in the copending application of Keith and Burk, Serial No. 683,931, filed September 16, 1957, C_4 to C_9 n-paraffinic-containing materials are isomerized at relatively low temperatures while obtaining satisfactory conversion to isomeric structures. This isomerizing process includes contacting a C_4 to C_9 n-paraffin in the vapor phase with a noble metal-Friedel-Crafts component-alumina catalyst at a temperature of about 150 to 450° F., a space velocity in most cases of about 0.5 to 10:1 weights of n-paraffin per weight of catalyst per hour (WHSV) in the presence of free hydrogen and while providing about 0.05 to 35% of a hydrogen halide based on the n-paraffin. When following this procedure the amount of isomer structures in the product are sufficient such that the overall product stream can be used directly in a gasoline pool without requiring distillation for separating the n-paraffins from the product. The feeds employed in this process are usually pretreated to lower the amount of aromatic and naphthalene impurities contained therein since the impurities can have deleterious effects on catalysts of this type. These feeds may contain substantial amounts of impurities, for instance, up to about 10 percent aromatics, up to about 20 percent naphthalenes, and up to about 0.004 or more percent sulfur. However, when following the two-stage procedure of the present invention, in which this process is employed in the second stage, a feed containing aromatics as well as n-paraffins can be employed in the first stage in the presence of a hydrogen halide-stable catalyst to provide appreciable isomerization of the n-paraffins to enhance the octane rating of the feed, e.g. above about 94, and at the same time providing hydrogenation of the aromatics. The product from the first stage is further enhanced in octane rating in the second stage at less severe temperature conditions than those employed in the first stage and using equivalent or greater space velocities for a given conversion of n-paraffin to isoparaffin than the space velocities employed in the process disclosed in

the above-mentioned copending application, Serial No. 683,931. In other words, due to the use of our initial conversion zone the second stage of this invention can provide greater amounts of high octane product from a feedstock containing aromatic poisons for the second stage catalyst than would be obtained by employing the second stage alone. At set forth in the above copending application, hydrogen halide is advantageously included in the hydrogen recycle gases employed in this process. Accordingly, another advantageous feature of our two-stage procedure is the simplicity and the interdependent relationship between the two stages allowing use of common hydrogen recycle gases containing hydrogen halide in each stage since the catalyst employed in the first stage is stable in the presence of hydrogen halide.

In the first stage (stage I) of the present process, which can be conducted in the presence of hydrogen recycle gases containing hydrogen halide at atomic weight between 35 and 85, some isomerization of C_5 to C_9 n-paraffins is effected along with the hydrogenation of aromatics, e.g. benzene and toluene. Benzene, when present in substantial amounts, is converted to methyl cyclo pentane and cyclo hexane which are tolerable in the first stage and are tolerable in the second stage in amounts less than about 12 weight percent based upon the hydrocarbon feed. When large amounts of naphthenes are present in the feed, for instance, in amounts above about 12 and up to about 20 or 25 weight percent, temperatures from about 575° F. to 650° F. can be provided in the first stage to reduce the naphthene content of the feed to less than about 12 weight percent and preferably less than about 10 weight percent, e.g. about 1 to 9 weight percent, by selectively cracking the naphthenes to, for instance, isoparaffins and other products, while effecting some isomerization of C_5 to C_9 n-paraffins along with the hydrogenation of aromatics. The selectivity to C_5 and higher products for the isomerization of n-pentane in the first stage is generally up to about 94 volume percent or more. The product of the first stage or any portion thereof is charged to the second stage (stage II) which is characterized by good selectivity, for instance generally above about 97% and frequently above about 98%, for the isomerization of normal pentane to iso-pentane.

In the initial stage of the process of the present invention, C_5 to C_9 n-paraffinic materials in the hydrocarbon feed are converted to isomeric structures at relatively intermediate temperatures in the presence of free hydrogen with a noble metal-boria-alumina catalyst which is easily regenerable, exhibits good activity as well as good aging characteristics and is stable in the presence of hydrogen halide employed in the second stage of the process. Another highly advantageous feature provided by the use of this catalyst in the initial stage lay in the lowering of the aromatic and, when present in amounts above about 12 weight percent and under favorable temperature conditions, naphthene ingredients contained in the feed since the catalyst has a relatively high tolerance limit for these as well as other ingredients. Thus, for instance, feeds containing up to about 0.004 or more percent sulfur, up to about 10 percent aromatics and up to about 20 percent naphthenes can be tolerated.

The catalyst employed in the initial stage of the present process includes catalytically effective amounts of a noble or platinum group metal and boria supported on an alumina base. The catalyst generally contains about 0.01 to 2 weight percent, preferably 0.1 to 1 weight percent, of one or more of the platinum metals of group VIII, that is platinum, palladium, rhodium, ruthenium, osmium or iridium. The small amount of noble metal may be present in the metallic form or as a sulfide, oxide or other combined form. The metal may interact with other constituents of the catalyst, but if during use the noble metal be present in metallic form, then it is preferred that it be so finely divided that it is not detectable by X-ray diffraction means, i.e. that it exists as crystals of less than 50

Angstrom units size. Of the noble metals platinum, palladium and rhodium are preferred.

The boria component is surface dispersible on the support and seems essentially inert to hydrogen halide. It is employed in amounts sufficient to enhance the life of the alumina support and such amounts are, therefore, preferably added in direct proportion to the area of the support. For instance, the amount of boria will usually be about 3 or 5 to 20 weight percent and preferably about 8 to 15 weight percent of the catalyst. These amounts are particularly effective on alumina having surface areas of about 350 to 550 square meters per gram (BET) before use.

In order for the catalyst to maintain its activity for long periods of time when isomerizing the C_5 to C_9 n-paraffins, it is highly desirable to provide a hydrogen halide of atomic weight between 35 and 85, e.g. HCl, HBr and their mixtures, in the reaction zone. The hydrogen halide can be added along with or in the n-paraffin feed and preferably in hydrogen recycle gases employable in either stage of the present process. The hydrogen halide is provided in an amount of at least about 1 up to about 25 percent, based on the hydrocarbon feed, preferably at least about 1% up to about 20% and advantageously about 5 to 15 weight percent of hydrogen halide or hydrogen halide of a hydrogen halide-producing material based on the hydrocarbon feed. The addition of the hydrogen halide in these concentrations is continued over the processing period in order to maintain an adequate concentration of this component and insure the stability of the catalyst against undue aging. The hydrogen halide can be added separately to the reaction zone, in the hydrogen-containing recycle gases, or in the n-paraffin feedstock.

Instead of supplying the hydrogen halide with an atomic weight between 35 and 85 as such, an organo-halogen compound or other substance which will produce the hydrogen halide under the isomerization conditions can be employed. Suitable hydrogen halide precursors of this type include the elemental halogens, chlorine, bromine and fluorine; mono- and polyhalo-alkanes such as carbon tetrachloride, chloroform and tertiary butyl chloride; or other available materials which will be converted under the conditions of isomerization to provide the hydrogen halide.

The noble metal and boria constituents of the catalyst are deposited on an absorptive alumina base of the activated or calcined type. The alumina base is usually the major component of the catalyst, generally constituting at least about 75 weight percent on the basis of the catalyst and preferably at least about 80 to 90 percent. The catalyst base is an activated or gamma-alumina such as those derived by calcination of amorphous hydrous alumina, alumina monohydrate, alumina trihydrate or their mixtures. The catalyst base precursor most advantageously is a mixture predominating in, or containing a major proportion of, for instance about 65 to 95 weight percent, one or more of the alumina trihydrates bayerite I, bayerite II (randomite) or gibbsite, and about 5 to 35 weight percent of alumina monohydrate (boehmite), amorphous hydrous alumina or their mixture. The alumina base can contain small amounts of other solid oxides such as silica, magnesia, natural or activated clays (such as kaolinite, montmorillonite, halloysite, etc.), titania, zirconia, etc., or their mixtures. Although the components of the catalyst can vary as stated, the preferred catalyst contains platinum and boria deposited on activated alumina.

The first stage reaction conditions used in the method of the present invention include a temperature sufficient to maintain the n-paraffin feed in the vapor phase under the pressure employed. Generally, this temperature will be from about 200 to 750° F., preferably about 500 to 650° F., while the pressure will be superatmospheric ranging from about 400 to 1500 p.s.i.g., preferably about 400 to 750 p.s.i.g. The catalyst can be used as a fixed,

moving or fluidized bed or in any other convenient type of handling system. The fixed bed system seems most advantageous at this time and the space velocity will in most cases be from about 0.5 to 20:1, preferably about 0.75 to 10:1, weights of n-paraffin per weight of catalyst per hour (WHSV).

Free or molecular hydrogen must be present in our first stage reaction system and the hydrogen to n-paraffin molar ratio will usually be from about 0.01 to 20:1 or more, preferably about 2 or 3 to 10:1. Conveniently, the hydrogen concentration is maintained by recycling hydrogen-rich gases from the reaction zones of either the first or second stages. These gases contain hydrogen halide at least after the initial processing period and as there is usually no substantial consumption of the halide after this period the desired concentration in the feed can be maintained for use in the second reaction zone merely by recycling the hydrogen halide-containing gases, for instance, with a hydrogen halide concentration on the order set forth above.

As previously stated the preferred catalyst base material is an activated or gamma-alumina made by calcining a precursor predominating in alumina trihydrate. An alumina of this type is disclosed in U.S. Patent No. 2,838,444. The alumina base is derived from a precursor alumina hydrate composition containing about 65 to 95 weight percent of one or more of the alumina trihydrate forms gibbsite, bayerite I and bayerite II (randomite) as defined by X-ray diffraction analysis. The substantial balance of the hydrate is amorphous hydrous or monohydrate alumina. Trihydrates are present as well-defined crystallites, that is, they are crystalline in form when examined by X-ray diffraction means. The crystallite size of the precursor alumina trihydrate is relatively large and usually is in the 100 to 1000 Angstrom unit range. The calcined alumina has a large portion of its pore volume in the pore size range of about 100 to 1000 Angstrom units generally having about 0.1 to about 0.5 and preferably about 0.15 to about 0.3 cc./g. of pore volume in this range. As described in these applications the calcined catalyst base can be characterized by large surface area ranging from about 350 to about 550 or more square meters/gram when in the virgin state as determined, for example, by the BET adsorption technique. A low area catalyst base prepared by treating the predominantly trihydrate base precursor is described in U.S. Patent No. 2,838,445. This base when in the virgin state has substantially no pores of radius less than 10 Angstrom units and the surface area of the catalyst is less than 350 square meters/gram and most advantageously is in the range of about 150 to 300 square meters/gram.

The platinum group metal, e.g. platinum, component of the catalyst can be added to the alumina base by known procedures. For instance, the platinum metal component can be deposited on a calcined or activated alumina, but it is preferred to add the platinum metal component to the alumina hydrate base precursor. Thus platinum can be added through reaction of a halogen platinum acid, for instance, fluoro-, chloro-, bromo- or iodo-platinic acid, and hydrogen sulfide in an aqueous slurry of the alumina hydrate. The hydrogen sulfide can be employed as a gas or an aqueous solution. Alternatively, the platinum component can be provided by mixing an aqueous platinum sulfide sol with the alumina hydrate. This sol can be made by reaction in an aqueous medium of a halogen platinic acid with hydrogen sulfide. The alumina hydrate containing the platinum metal can be dried and calcined usually at a temperature from about 750 to 1200° F. or more to provide the activated or gamma alumina modifications. The boria component can be added to the catalyst in any stage of its preparation. It may be incorporated in the support either before or after the addition of the group VIII

metal, by impregnation from a hot, heated or boiling solution of water. It is frequently added to the catalyst after it has been formed by tableting or extrusion and calcined. After the boria is added according to this procedure, the catalyst can be recalcined.

The catalyst of the initial stage of the present invention can be easily regenerated employing conventional procedures, for instance by subjecting it to an oxygen-containing gas at temperatures sufficient to burn off carbon deposited on the catalyst during the conversion of petroleum hydrocarbon feedstock. This oxygen-containing gas, e.g. an oxygen-nitrogen mixture, can contain about 0.01 weight percent to 5 weight percent oxygen but preferably contains about 0.5 to 1.5 weight percent oxygen and is introduced at a flow rate such that the maximum temperature at the site of the combustion is below about 1000° F.

In the second stage of the present process, the product from the first stage is treated with a solid catalyst which is useful in the isomerization of the C₅ to C₉ n-paraffins in the presence of free hydrogen and at relatively low temperatures to afford highly satisfactory yields of isomer products. This catalyst, when employed under proper conditions, has an excellent stability against aging. Due to the high isomer content of the resulting product from the second stage, a given refiner may find that it can be blended directly into his gasolines which avoids the necessity for providing distillation facilities to separate the unconverted n-paraffins. However, even if such facilities need to be provided in order to obtain products more concentrated in isomeric structures the catalyst of the second stage still provides increased conversion to branched isomers as compared with others previously available.

The catalyst used in the second stage includes catalytically effective amounts of a noble or platinum group metal, an aluminum halide Friedel-Crafts component and at least ultimately in the reaction zone, a hydrogen halide of atomic weight between 35 and 85, all of which are supported on an alumina base. The catalyst generally contains about 0.01 to 2 weight percent, preferably 0.1 to 0.75 weight percent, of one or more of the platinum metals of group VIII, that is platinum, palladium, rhodium, ruthenium, osmium or iridium. The small amount of noble metal may be present in the metallic form or as a sulfide, oxide or other combined form. The metal may interact with other constituents of the catalyst, but if during use the noble metal be present in metallic form then it is preferred that it be so finely divided that it is not detectable by X-ray diffraction means, i.e. that it exists as crystals of less than 50 Angstrom units size. Of the noble metals, platinum is preferred.

The aluminum halide Friedel-Crafts component usually is about 2 to 50 weight percent, preferably about 10 to 30 weight percent, of the catalyst and this component can be, for instance, AlCl₃, AlBr₃ and similar metal halides where one or more of the anions are replaced with another anion such as hydroxide. Mixtures of these Friedel-Crafts components can also be used; aluminum chloride is, however, the preferred Friedel-Crafts component.

A hydrogen halide of atomic weight between 35 and 85 is provided in the reaction zone of the second stage in order for the catalyst to maintain the activity of the catalyst for long periods of time when isomerizing the C₅ to C₉ n-paraffins from the first stage. The amounts, manner of employment and types of hydrogen halide provided in the second stage are essentially the same as in the first stage described above. Thus we have found that the catalyst should contain about 0.5 to 15% or more of the hydrogen halide. The hydrogen halides of atomic weight between 35 and 85 include, for instance, hydrogen chloride and hydrogen bromide and their mix-

tures and preferably the amount of this component on the alumina base is less than about 10% of the catalyst. Usually this halide will be added to the catalyst after it is placed in the isomerization reaction. Conveniently this can be done by including in the charge stock from the initial stage about 1 to 20 or 25 weight percent, advantageously about 5 to 15 weight percent of the hydrogen halide or of a hydrogen halide-producing material. The addition of the hydrogen halide in these concentrations based on the n-paraffin in the second stage, as in the case of the first stage, is continued over the processing period in order to maintain an adequate concentration of this component on the alumina base and insure the stability of the catalyst against undue aging. The hydrogen halide can be added separately to the reaction system, in the hydrogen-containing recycle gases or in the charge stock from the initial stage. Also the hydrogen halide might be added to the catalyst before charging it to the reactor.

Instead of supplying the hydrogen halide of atomic weight between 35 and 85 as such, an organo-halogen compound or other substance which will produce the hydrogen halide under the isomerization conditions can be employed. Suitable hydrogen halide precursors include the elemental halogens, chlorine and bromine; mono- and polyhalo-alkanes such as carbon tetrachloride, chloroform and tertiary butyl chloride; or other available materials which will be converted under the conditions of isomerization to obtain the hydrogen halide. Most advantageously about 5 to 15 weight percent of hydrogen chloride is employed as the hydrogen halide on the catalyst and is supplied during the processing period.

The noble metal, Friedel-Crafts and hydrogen halide, of atomic weight between 35 and 85, constituents of the catalyst are deposited on an absorptive alumina base of the activated or calcined type, as described in connection with the catalyst employed in the first stage. The base is usually the major component of the catalyst, constituting about 40 to 88 or 98 weight percent, preferably at least about 50%. The catalyst base is an activated or gamma-alumina such as those derived by calcination of amorphous hydrous alumina, alumina monohydrate, alumina trihydrate or their mixtures, for instance as in the catalyst of our first stage reaction zone. The catalyst base precursor most advantageously is a mixture predominating in, or containing a major proportion of, for instance about 65 to 95 weight percent, one or more of the alumina trihydrates bayerite I, bayerite II (randomite) or gibbsite, and about 5 to 35 weight percent of alumina monohydrate (boehmite), amorphous hydrous alumina or their mixture. The alumina base can contain small amounts of other solid oxides such as silica, magnesia, boria, natural or activated clays (such as kaolinite, montmorillonite, halloysite, etc.), titania, zirconia, etc., or their mixtures. Although the components of the catalyst can vary as stated, the preferred catalyst contains platinum, aluminum chloride and hydrogen chloride deposited on activated alumina.

The isomerization reaction conditions used in the second stage of the method of the present invention include a temperature sufficient to maintain the n-paraffin feed in the vapor phase under the pressure employed. Generally, this temperature will be from about 150 to 450° F., preferably about 250 to 400° F., while the pressure will be superatmospheric, ranging from about 50 to 1000 p.s.i.g., preferably about 200 to 600 p.s.i.g. The catalyst can be used as a fixed, moving or fluidized bed or in any other convenient type of handling system. The fixed bed system seems most advantageous at this time and the space velocity will in most cases be from about 0.5 to 10:1 weights of n-paraffin per weight of catalyst per hour (WHSV).

Free or molecular hydrogen must also be present in the second stage of our reaction system and the hydrogen

to n-paraffin molar ratio will usually be from about 0.01 to 15:1 or more, preferably about 1 to 8:1. Conveniently, the hydrogen concentration is maintained by recycling hydrogen-rich gases from the reaction zone. These gases contain hydrogen halide at least after the initial processing period and as there is usually no substantial consumption of the halide after this period the desired concentration in the feed can be maintained merely by recycling the hydrogen gases containing hydrogen halide of atomic weight between 35 and 85 since, for instance, the hydrogen halide concentration can with advantage be about 0.5 to 35 weight percent of the recycled gases.

A convenient manner in which the catalyst of the second stage of the present invention can be prepared is to add the Friedel-Crafts component to the base containing the platinum metal component. It is highly desirable to keep the catalyst protected from moisture to avoid hydrolysis and the resulting loss of aluminum halide from the catalyst. Thus it is most advantageous to employ this catalyst under essentially anhydrous conditions including the provision of the hydrogen halide in anhydrous form. During regeneration of the catalyst to remove carbonaceous deposits by burning in an oxygen-containing gas, some aluminum halide may be lost. Thus, it may be necessary to add additional amounts of this halide as by sublimation before continuing the isomerization.

Even though the catalysts used in each of the first and second stages can be employed directly in the isomerization system, it is preferred that they be pretreated with free or molecular hydrogen or a mixture of hydrogen and hydrogen halide. For instance, the catalyst used in the first stage can be pre-reduced or preactivated by treatment with hydrogen at an elevated temperature, for instance about 800 to 1000° F. The catalyst used in the second stage can be heated to about 650° F. in a slowly flowing stream of hydrogen or hydrogen-hydrogen chloride mixture for a period of time sufficient to activate the catalyst. It may be desirable to employ lower temperatures in the pretreatment of the second stage catalyst to avoid undue loss of aluminum halide by sublimation even though this may decrease the rate of activation. After the activation the pressure can be increased as desired and the product from the first stage is charged to the reaction system. Generally, the activity of the catalyst increases during the initial portion of operation and then holds a high level of activity for long processing periods, thus exhibiting good life or resistance to aging. It seems possible that upon the addition of the n-paraffin feed the catalyst is comprised of the noble metal and a complex of the Friedel-Crafts component, the n-paraffin and the hydrogen halide supported on the alumina base.

As previously stated the preferred catalyst base material is an activated or gamma-alumina made by calcining a precursor predominating in alumina trihydrate as exemplified in U.S. Patents 2,838,444 and 2,838,445. The platinum metal component of our catalysts can be added to the alumina base by known procedures described in connection with the preparation of the catalyst of the first stage.

The Friedel-Crafts component can then be added to the catalyst according to known procedures for adding such materials to solid absorptive bases, for instance by sublimation. The addition of the Friedel-Crafts component to the high area catalyst base of U.S. Patent No. 2,838,444 has been found to decrease the surface area, for instance frequently in proportion to the amount of Friedel-Crafts component added. Use of the catalyst in the isomerization system or hydrogen pretreatment seems to tend to increase the area apparently through loss of the Friedel-Crafts component.

The following specific example will serve to illustrate the invention but it is not to be considered limiting.

EXAMPLE I

(A) Preparation of noble metal-alumina composition

A noble metal-alumina composition of the kind described in U. S. Patent No. 2,838,444, can be employed in preparing the catalyst used in the process of our invention. The composition of this application can be made as follows. Pure aluminum metal is dissolved in pure hydrochloric acid, and the resulting solution is mixed with deionized water to form an aqueous aluminum chloride solution and an alumina gel is prepared equivalent to approximately 65 grams of Al_2O_3 per liter. A separate deionized water solution of NH_4OH is prepared containing approximately 65 grams of ammonia per liter. These two reagents in approximate volume ratio of 1:1 are intimately mixed as a flowing stream at a pH of 8.0. The flowing stream is passed to a stoneware container and an alumina hydrate is visible. The precipitated hydrate is filtered from the mother liquid and washed to <0.2% chloride by successive filtrations and reslurrying in deionized water until the desired chloride concentration is reached. In each reslurrying ammonia is added to give a pH of about 9. The washed hydrate is covered with water in a container and aged at about 90° F. until it is approximately 70% trihydrate, the remaining being substantially of the amorphous or monohydrate forms. The total hydrate composition is comprised of 42% bayerite, 18% randomite, 11% gibbsite, 20% boehmite, and 9% amorphous as determined by X-ray diffraction analysis. The aged hydrate is mixed with deionized water in a rubber lined container to provide a slurry of about 7 weight percent Al_2O_3 at a pH of about 8.0. A chloroplatinic acid solution in deionized water (0.102 gram platinum per milliliter) is stirred into the slurry and the slurry is then contacted with a deionized water solution which has been saturated with H_2S at 78° F. to precipitate the platinum. The pH of the slurry is adjusted to 6.0 to 6.5 by ammonium hydroxide addition and the solids of the slurry are dried on a horizontal drum drier to give a powder of generally less than 20 mesh. The drum dried powder is mixed in a planetary type dough beater with sufficient deionized water to indicate 26 weight percent water on a Central Scientific Company Infra-Red Moisture Meter containing a 125 watt bulb, Cat. No. 26675. The resulting mixture is forced through a die plate having holes $\frac{1}{16}$ " in diameter bolted to a $\frac{3}{16}$ " welding engineers screw extruder. The resulting strands are broken to particles of length varying generally between about $\frac{1}{16}$ " to 1".

The particles are dried at 230° F. and calcined by heating to 925° F. in a flow of nitrogen gas followed by a flow of air while the composition is maintained at a temperature in the range of 865° F. to 920° F. The composition thus produced analyzes about 0.6 weight percent of platinum which is in sufficiently divided form so as to exhibit by X-ray diffraction studies the substantial absence of crystallites or crystals of size larger than 50 Angstrom units. After the calcination the composition has an area (BET method) within the range from about 350 to 550 square meters/gram.

(B) Preparation of noble metal-boria-alumina catalyst

A platinum-alumina composition prepared essentially as described above, except that air was used for the complete calcination procedure and containing about 0.6% platinum was employed in preparing the noble metal-boria-alumina catalyst by the following procedure. 300 g. of the platinum-alumina composition were weighed into a 6" crystallizing dish. 59 g. of H_3BO_3 were dissolved in 279 ml. of deionized water by heating to boiling. The hot boric acid solution was poured over the catalyst and stirred thoroughly with a rubber spatula. The catalyst was placed in a forced air drying oven, set at 140° C., for 4 hours. The catalyst was stirred occasionally while drying. The oven dried catalyst was trans-

ferred to a sagger and placed in a muffle furnace pre-heated to 1000° F. The catalyst was held at 1000° F. for 2 hours and cooled in a desiccator. Analysis: 9.95% B_2O_3 .

An example of pre-activation follows: 40 grams of this catalyst were supported on glass beads in the center of a 1-inch I. D. Universal Stainless Steel Reactor. The reactor was set in place in a bronze-block furnace controlled by "Microswitch" thermostats. The catalyst was heated to 800° F. under atmospheric pressure of pure hydrogen flowing at about 2 cu. ft./hr. These conditions were maintained for 16 hours. At this time the reactor is cooled to operating temperatures and reaction conditions are established for processing the paraffin feed.

(C) Preparation of noble metal-aluminum halide-alumina catalyst

A platinum-alumina catalyst prepared essentially as described above in Example I(A), except that air was used for the complete calcination procedure and containing about 0.6 percent platinum was employed in the process of the present invention by the following procedure. A one-liter, three-necked flask was fitted with a heating mantle, thermometer and an air inlet line having a drying tower filled with Drierite. The flask was fastened to a Syntron Paper Jogger which provided agitation of the catalyst during the impregnation. The flask was swept out with dry air for about 10 minutes. 150 grams of the platinum-alumina catalyst and 45 grams of aluminum chloride were charged to the flask. The air was turned off, the flask was stoppered and the drying tower was disconnected from the air line. Heating of the flask was begun and the temperature of the mixture was brought slowly to approximately 445° F. in about three hours. The heat was turned off and the catalyst was cooled and transferred to a moisture-tight container. The resulting catalyst contained 19.3 weight percent aluminum chloride based upon the platinum-alumina composition.

(D) The two stage process

(1) ANALYSIS OF FEEDSTOCK

Feed (wt. percent)

45	C_3 -----	-----
	i-C ₄ -----	-----
	n-C ₄ -----	-----
	i-C ₅ -----	0.7
	n-C ₅ -----	28.6
50	2,2 dimethyl benzene -----	-----
	2,3 dimethyl benzene + 2 methyl pentane -----	8.4
	3 methyl pentane -----	9.6
55	n-C ₆ -----	36.2
	MCP -----	11.5
	CyC ₆ -----	0.9
	Benzene -----	3.1
	i-C ₇ -----	2.2
60	i-C ₈ -----	33.2

(2)

The present invention is illustrated by Run A, presented below in Table I, which was conducted under the conditions specified above for the two-stage process of the present invention. The results are also presented in this table. The catalyst employed in stage I was prepared by essentially the same procedure set forth in Example I(B) above except that the catalyst comprised 0.6 percent platinum and 10 percent boria on alumina. The catalyst employed in stage II was prepared by essentially the same procedure set forth in Example I(C) above except that the catalyst comprised 0.6 percent platinum and 30 percent aluminum chloride on alumina. The alumina chloride concentration is substantially maintained by adding aluminum chloride from a saturator to the product of the first stage.

11
TABLE I

Feed	Run A	
	Stage I	Stage II
	Same feed analyzed in Example I (D) (1)	Product from Stage I
Condition:		
Wt. percent HCl based on feed.....	12.5	12.5
Pressure, p.s.i.g.....	500	500
Temperature, °F.....	625	300
WHSV.....	3	2
H ₂ /HO Mole Ratio.....	5.6	5.6
Product:		
C ₃	1.4	0.9
1-C ₄	0.9	2.0
n-C ₄	0.5	0.6
1-C ₅	17.4	21.0
n-C ₅	14.8	11.5
2, 2 DMB.....	3.9	11.5
2, 3 DMB+2 MP.....	23.1	24.2
3 MP.....	18.5	11.2
n-C ₆	13.3	7.6
MCP.....	9.3	5.1
CyC ₆	1.9	4.4
Benzene.....	0.005	0.0001
Yields:		
1-C ₃	54.0	64.6
1-C ₅	75.2	86.0
2, 2 DMB.....	7.2	20.8
Selectivity C ₅ (%).....	97.2	99.3

It is claimed:

1. In a method for isomerizing C₅ to C₉ n-paraffins in a feed containing aromatics, the steps comprising contacting said n-paraffins under first stage conditions with a first stage catalyst at a temperature of about 200 to 750° F. and in the presence of free hydrogen to produce a first stage reaction product, contacting the first stage reaction product under second stage conditions with a second stage catalyst at a temperature from about 150 to 450° F. and in the presence of free hydrogen and while providing about 1 to 25 percent of a hydrogen halide with an atomic weight between 35 and 85 based on the first stage reaction product; said first stage catalyst consisting essentially of about 0.01 to 2% of a platinum group noble metal and about 3 to 20% of boria on activated alumina and said second stage catalyst consisting essentially of about 0.01 to 2% of a platinum group noble metal and about 2 to 50% of an aluminum halide Friedel-Crafts component on activated alumina.

2. In a method for isomerizing C₅ to C₉ n-paraffins in a feed containing aromatics, the steps comprising contacting said n-paraffins under first stage conditions with a first-stage catalyst at a temperature of about 200 to 750° F. and in the presence of free hydrogen while providing about 1 to 25 percent, based on the feed, of hydrogen halide with an atomic weight between 35 and 85 to produce a first stage reaction product, contacting the first stage reaction product under second stage conditions with a second stage catalyst at temperatures from about 150 to 450° F. and in the presence of free hydrogen while providing about 1 to 25 percent of a hydrogen halide with an atomic weight between 35 and 85, based on the first stage reaction product; said first stage catalyst consisting essentially of about 0.01 to 2 percent of a platinum group noble metal and about 5 to 20 percent of boria on activated alumina and said second stage catalyst consisting essentially of about 0.01 to 2 percent of a platinum group noble metal and about 2 to 50 percent of an aluminum halide Friedel-Crafts component on activated alumina.

3. In the method of claim 2 wherein the platinum

group noble metal of the second stage catalyst is platinum.

4. In a method of claim 3 wherein the first stage temperature conditions are from about 500 to 650° F.

5. In a method for isomerizing C₅ to C₉ n-paraffins in a feed containing aromatics, the steps comprising contacting said n-paraffins under first stage conditions with a first stage catalyst at temperatures of about 500 to 650° F., superatmospheric pressure, and the presence of free hydrogen while providing about 1 to 25%, based on the feed, of hydrogen halide with an atomic weight between 35 and 85 to produce a first stage reaction product of enhanced octane rating and containing hydrogenated aromatics, and contacting the first stage reaction product under less severe second stage conditions, to further enhance the octane rating of the first stage reaction product, with a second stage catalyst at temperatures from about 250 to 400° F., in the presence of free hydrogen and while providing about 1 to 25% of a hydrogen halide with an atomic weight between 35 and 85, based on the first stage reaction product; said first stage catalyst consisting essentially of about 0.01 to 2% of a platinum group noble metal and about 5 to 20% of boria on activated alumina and said second stage catalyst consisting essentially of about 0.01 to 2% of a platinum group noble metal and about 2 to 50% of an aluminum halide Friedel-Crafts component on activated alumina.

6. The method of claim 5 wherein the first stage catalyst consists essentially of about 0.1 to 1 weight percent of a platinum group noble metal and about 8 to 15 weight percent of boria on activated alumina and the second stage catalyst consists essentially of about 0.1 to 0.75 weight percent of a platinum group noble metal and about 10 to 30 weight percent of an aluminum halide Friedel-Crafts component on activated alumina.

7. The method of claim 5 wherein the first stage catalyst consists essentially of about 0.1 to 1 weight percent of platinum and about 8 to 15 weight percent of boria on activated alumina and the second stage catalyst consists essentially of about 0.1 to 0.75 weight percent of platinum and about 10 to 30 weight percent of aluminum chloride on activated alumina.

8. The method of claim 7 wherein the first stage conditions include a pressure of about 400 to 1500 p.s.i.g. and a hydrogen to n-paraffin molar ratio from about 0.01 to 20:1 and the second stage conditions include a pressure of about 50 to 1000 p.s.i.g. and a hydrogen to n-paraffin molar ratio from about 0.01 to 15:1.

9. The method of claim 8 wherein the activated alumina of the first and second stage catalysts is derived by calcination of an alumina hydrate precursor consisting essentially of about 65 to 95% of alumina trihydrate and about 5 to 35% of a member selected from the group consisting of amorphous hydrous alumina, alumina monohydrate and their mixture, and the activated alumina has an area of about 350 to 500 square meters per gram.

10. The method of claim 9 wherein the n-paraffin is pentane.
